UNITED STATES PATENT OFFICE.

EMMA HAFNER, OF PHILADELPHIA, PENNSYLVANIA, ASSIGNOR TO WALTER F. PEET AND EDWARD B. PEET, BOTH OF PHILADELPHIA, PENNSYLVANIA, TRADING AS FIRM OF PEET BROTHERS, OF PHILADELPHIA, PENNSYLVANIA.

DESIGN FOR A DISPLAY-CARD OF HOOKS AND EYES.

43,742.

Specification for Design.

Patented Mar. 25, 1913.

Application filed October 4, 1912. Serial No. 723,953. Term of patent 14 years.

To all whom it may concern:

Be it known that I, EMMA HAFNER, a citizen of the United States, and a resident of Philadelphia, Pennsylvania, have invented a new, original, and ornamental Design for a Display-Card of Hooks and Eyes, of which the following is a specification.

My design is fully shown in the accompanying drawing, in which—

Figure 1 represents a face view of the de-

sign, and Fig. 2 an end elevation of the same.

I claim:

The ornamental design for a display card of hooks and eyes, as shown.

EMMA HAFNER.
